Examination Report issued Aug. 4, 2016 in Israeli Patent Application No. 57968.

Primary Examiner — Karen E Kearney*Assistant Examiner* — Jennifer M Campbell(74) *Attorney, Agent, or Firm* — Oblon, McClelland, Maier & Neustadt, L.L.P.(57) **CLAIM**

The ornamental design for a cigarette-shaped consumable, as shown and described.

DESCRIPTION

The file of this patent contains drawings/photographs of FIGS. 1 and 6, executed in color. Copies of this patent with color drawings/photographs will be provided by the Office upon request and payment of the necessary fee.

FIG. 1 is a top, front perspective view of a cigarette-shaped consumable according to my design;

FIG. 2 is a bottom, front perspective view thereof;

FIG. 3 is a front elevational view thereof;

FIG. 4 is a back elevational view thereof;

FIG. 5 is a left side elevational view thereof, the right side elevational view being a mirror image of the left side elevational view;

FIG. 6 is a top elevational view thereof; and,

FIG. 7 is a bottom elevational view thereof.
